Primary Examiner — Jeffrey D Asch*Assistant Examiner* — S. Bryan Reinhold, Jr.(74) *Attorney, Agent, or Firm* — Seed Intellectual Property Law Group LLP(57) **CLAIM**

The ornamental design for a stripping tool for leafy vegetables and herbs, as shown and described.

DESCRIPTION

FIG. 1 is a perspective view of a stripping tool for leafy vegetables and herbs showing our new design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is a first bottom perspective view thereof; and,

FIG. 9 is a second bottom perspective view thereof.

The broken line showing of circular details in FIGS. 7 and 8 form no part of the claim.

1 Claim, 5 Drawing Sheets(56)
